UNITED STATES PATENT OFFICE.

AMOS F. SWEIGART, OF SOUTH HAMPTON, PENNSYLVANIA.

RAIL-JOINT FASTENING.

No. 900,351.

Specification of Letters Patent.

Patented Oct. 6, 1908.

Application filed September 10, 1907. Serial No. 392,173.

To all whom it may concern:

Be it known that I, AMOS F. SWEIGART, a citizen of the United States, residing at South Hampton, in the county of Bucks and State of Pennsylvania, have invented certain new and useful Improvements in Rail-Joint Fastenings, of which the following is a specification.

My invention relates to improvements in railway joint fastenings, or chairs, as used at the connecting point of adjoining rails.

The objects of my invention are, to provide novel means of connection adapted to hold the abutting rails in alinement, laterally, and at the same time prevent sagging of the ends under a load.

A further object is to hold the rails against any creeping effect, relative to the cross ties, and finally, to so arrange the fastening means that it may be applied without making holes in the rails, at any point along the trackway, as between, or on, the ties and which can be used to advantage in splicing, or repairing, broken rails.

With these objects in view, my invention consists of certain novel constructional combinations fully described hereinafter and shown in the several accompanying drawings, which form part of this specification, and in which like characters are used in designating like parts.

Figure 1, is a transverse sectional view through a rail, showing the application of my invention. Fig. 2, is a side elevation of a rail joint. Fig. 3, is a perspective view of a rail end, showing the notched edges used. Fig. 4, is a partial plan view, of a fastening member, broken away to show the tongue therein. Fig. 5, is a side elevation of the outer fastening member, drawn to a reduced scale, and looking from the interior, and Fig. 6, is a similar view of the inner fastening member.

As indicated in the drawings, the invention consists of an outer rolled, or cast metal, member 3, fitted closely to the rail, particularly between the head and flange, thus materially supporting the same, having a portion 3", level with the upper surface of the head, adapted to receive the wheel tread in its passage over the joint, thereby preventing wheel-hammering of the rail edges; integral with the upper, or fish plate, portion, is the lower or chair, portion 4, extending laterally below the rail flange almost to its center and intended to take the weight of a passing

load. On the opposite, or inner, side of the rail is a similar member 5, likewise closely fitted and having the chair portion 6, underlying the other side of the rail flange. 60 Throughout both of these members pass bolts 7, preferably four in number, and adapted to draw the two members 4 and 6, tightly together, clamping the rail ends contained in the fastenings rigidly in alinement. Within the said members 3 and 5, I form projecting tenons or tongues, 3' and 5', intersecting with and filling the notched recesses formed in the edges of the abutting rail flanges, and in such manner that lateral 70 movement of the rail fastenings is prevented, except it be accompanied by a corresponding movement of the rails; the reverse of this is obviously true, and if the fastenings be securely anchored or maintained, as indicated particularly in Fig. 2, in which the chair portions 4, and 6, are fitted between two ties, lateral movement of the joint is overcome.

I may also make use of the auxiliary plate 80 member 8, as shown in Fig. 1, in stiffening the construction, in which case I apply it to the inner member 5, by means of the bolts, or screws, 9, as an additional strengthening element. Furthermore in some cases, I prefer to make use of the construction indicated in Figs. 5 and 6, in which the chair portions 4 and 6, may be positioned between and against the inner sides of two adjacent ties, and the fish plate portions 3 and 5, rest 85 on the ties, or I may cut away the top surface of the tie, or ties, as may be necessary in applying the fastenings. I may also make minor modifications from the construction, as shown, without departing from the spirit of my invention. Therefore, I do not wish to be limited to the exact construction indicated.

Having thus described my invention what I claim as new and desire to secure by Letters Patent is:

In a rail joint, the combination with the meeting ends of adjacent rails having notched edges registering with each other, of an inner and outer fish plate portion fitting closely against the rails between the heads and flanges, the outer fish plate portion having an upwardly extending portion fitting closely against the head and level with the upper surface of the same, integral chair portions extending laterally below the rails provided with transverse bores in aline-

ment, tongues formed on said chair portions extending in the notched portions of the rails, bolts extending through said bores for securing said members together, and a reinforcing member secured on the inner fish plate member, for the purpose described.

In testimony whereof I have signed my

name to this specification in the presence of two subscribing witnesses.

AMOS F. SWEIGART.
